(57) **CLAIM**

I claim the ornamental design for a laser guided putting and swing aid for golfers, as shown and described.

DESCRIPTION

FIG. 1 is a perspective view of a laser guided putting and swing aid for golfers, showing my new design;

FIG. 2 is an exploded perspective view of the invention;

FIG. 3 is a front elevational view of the invention;

FIG. 4 is a rear elevational view of the invention;

FIG. 5 is a top plan view of the invention;

FIG. 6 is a bottom plan view of the invention;

FIG. 7 is a left-side elevational view of the invention, the right-side elevational view being a mirror image thereof; and,

FIG. 8 is a left-side elevational view of the invention, illustrating a clip of the invention in a downwardly-pivoted orientation.

The broken lines showing a laser beam pattern in FIG. 7 are included for the purpose of illustrating the invention in use, and forms no part of the claimed design.
